UNITED STATES PATENT OFFICE.

WALTER S. ADAMS, OF PHILADELPHIA, PENNSYLVANIA.

DESIGN FOR A TRUCK SIDE-BAR.

SPECIFICATION forming part of Design No. 29,309, dated September 6, 1898.

Application filed August 8, 1898. Serial No. 688,123. Term of patent 14 years.

To all whom it may concern:

Be it known that I, WALTER S. ADAMS, a citizen of the United States, residing at Philadelphia, county of Philadelphia, and State of Pennsylvania, have invented and produced a new and original Design for a Truck Side-Bar, of which the following is a specification; reference being had to the accompanying drawings, forming part of the same.

10 My invention has relation to the design for a side-bar for a truck-frame. The essential feature resides in its configuration.

In the drawings forming part of this specification, Figure 1 is a side elevation; Fig. 2, 15 a plan view, and Fig. 3 a sectional elevation through one part of the side-bar.

The side-bar comprises the inverted-U-shaped yokes 1 and 2, the yoke 1 being of greater vertical dimensions than 2, the central rectangular bar 3, extending between the 20 inner legs 4 5 of the said yokes, and the extensions 6 7 from the outer legs 8 9 of said yokes, the extension 6 being between the top and bottom of the leg 9 and the extension 7

lying vertically along the leg 8 and having 25 transverse apertures 10, the extension 6 having a recessed extension 11 at the end.

The legs 4 5 8 9 of both yokes are recessed at 12, as shown in Fig. 3 in section and in dotted lines, Figs. 1 and 2, the crown 13 of 30 the yoke 2 being swelled out and provided with an interior circular recess, the latter being indicated by dotted lines in Figs. 1 and 2.

The crown 14 of the yoke 2 is provided with 35 semicircular projections 15, and from said yoke extends an arm 16 over the bar 3.

Both of the yokes 1 and 2 are of greater transverse thickness than the parts 3 6 7.

Having described my invention, I claim—

The design for a truck side-bar, substantially as herein shown and described. 40

Signed at Philadelphia, county of Philadelphia, and State of Pennsylvania, this 5th day of August, 1898.

WALTER S. ADAMS.
